Primary Examiner—Melanie Tung*Assistant Examiner*—Susan Moon Lee(74) *Attorney, Agent, or Firm*—Trellis IP Law Group(57) **CLAIM**

We claim the ornamental design for a computer docking assembly, as shown and described.

DESCRIPTION

FIG. 1 is a perspective view from a side of a computer docking assembly.

FIG. 2 is a perspective view from another side of the invention in FIG. 1.

FIG. 3 is an end elevational view of the invention.

FIG. 4 is another end elevational view of the invention, opposed to the end shown in FIG. 3.

FIG. 5 is a side elevational view of the invention.

FIG. 6 is another side elevational view of the invention, opposed to the side shown in FIG. 5.

FIG. 7 is a top plan view of the invention; and,

FIG. 8 is a bottom plan view of the invention.
